UNITED STATES PATENT OFFICE.

JACK L. WALKER, OF DALLAS, TEXAS.

ATTACHMENT FOR ADDING-MACHINES.

1,290,432.

Specification of Letters Patent.

Patented Jan. 7, 1919.

Application filed August 21, 1916. Serial No. 115,986.

To all whom it may concern:

Be it known that I, JACK L. WALKER, citizen of the United States, residing at Dallas, in the county of Dallas and State 5 of Texas, have invented certain new and useful Improvements in Attachments for Adding-Machines, of which the following is a specification.

Adding machines are usually made in two 10 types, those which add but do not print or list the sums, and those which both add and list the sums.

My invention contemplates an attachment which may be connected with either 15 type of machine and constructed to print or list the sums as they are listed or accumulated by the adding machine. Where the adding machine lists the sums the attachment will form a duplicate listing device 20 so that sums which are added and listed by the machine, may at the same time be printed or listed on a separate sheet of paper or form fed to the attachment. If the adding machine does not list the sums, 25 they may be listed by the attachment.

In carrying out the invention I propose to arrange a printing device constructed with adjustable printing units so that the units may be adjusted by connection with 30 those elements of the adding machine which are adjusted to list or add the sums whereby the printing units will print the same amount as is added by the machine.

It is quite obvious that this invention may 35 be reduced to practice in various forms and the manner of operating it is likewise capable of considerable variation.

As an illustration of the invention I have shown an attachment adapted to be arranged 40 at the side of a listing adding machine and having a plurality of number printing wheels. Means for adjusting the wheels so that they will print the same numbers as the adding machine, is connected to the type- 45 bar carriers of the adding machine. The attachment is pivoted and means is provided and operated by the machine for swinging the printing wheels downward so as to print the numbers at substantially the same time 50 as they are printed by the machine. The attachment also includes various other elements which will be more specifically pointed out.

The invention will be more readily under- 55 stood from a perusal of the following specification and by reference to the accompany-

ing drawing in which an example of the invention is shown, and wherein:

Figure 1 is a side elevation of an adding machine with an embodiment of my invention in position at the side thereof. 60

Fig. 2 is a plan view of the same,

Fig. 3 is a detail of the ribbon feed,

Fig. 4 is a longitudinal sectional view of the attachment, 65

Fig. 5 is a detail locking and tripping means, and Fig. 6 is a detail of the shaft rocking means.

In the drawings the numeral 1 designates a horizontal supporting frame mounted at 70 one side on angular legs 2 and 3 respectively and overhanging a carrier 4. The legs are secured to the usual shelf 5 which is mounted at one side of the adding machine 6. From the outer side of the frame and opposite 75 the leg 2, an arm 7 depends. The rear end of the carrier is pivoted to the leg 2 and the arm 7 as indicated at 8. The carrier is rectangular in plan and has near its forward end a transverse shaft 9 fixed against 80 rotation. A plurality of disks or wheels 10 are loosely confined on this shaft and each carries at one side a small pinion 11, which acts to revolve the wheel to which it is attached. Each wheel has on its periphery 85 numerical characters ranging from zero to nine, but between the zero and the nine there is a gap such as is common in numbering machines.

The wheels are normally disposed with 90 their gaps downward so that if the carrier was depressed, no character would be printed. Longitudinal rack bars 12 are arranged within the carrier and have their forward ends engaging on the pinions 11. 95 These bars are also supported intermediate their ends on pinions 13 mounted on a fixed transverse shaft 14. Each rack bar carries on its upper side and at its rear end a stepped stop lug which has steps or stops 100 16 on its face equal in number to number of characters on a wheel. A detent 17 is positioned in the path of each lug and according to its elevation limits the forward movement of the rack bar correlated therewith, 105 the parts being so timed that the movement of the rack bar the distance of one step is sufficient to revolve the correlated wheel the peripheral distance from one character to the next character.

Each rack bar 12 has a depending arm 18 to which the rear end of a coiled spring

19 is attached, the forward ends of said springs being attached to a cross bar 20. These springs act to pull the bars 12 forward and revolve the pinions 11. The bars 5 are held against forward movement by a yoke 21 having its cross bars 22 in the path of the arms 18 and the lower bars 22 acting to hold the arms. A pair of coiled springs 23 have their forward ends attached to the 10 inner sides of the carrier and their rear ends to the upper ends of the yoke 21 above the pivot point of the latter. The springs 23 are stronger than the springs 19 and overcome the latter so that the bars 12 are returned to their normal positions. A transverse stop rod 24 impinged by the arms 18 limits the rearward or return movement of the rack bars 12.

The detents 17 depend from the forward 20 ends of bell-crank levers 25 pivoted on a cross shaft 26, the opposite leg of each lever being attached to one end of a coiled spring 27 which has its opposite end attached to a cross bar 28 secured in the carrier. These 25 springs act to swing the levers so that detents are elevated and means hereinafter described is provided for controlling the swing of the levers and consequently the elevation of the detents. On the vertical 30 portion of each lever 25 a forwardly projecting finger 29 is provided. A plurality of latches 30 are pivoted on a cross shaft 31 mounted in the carrier and each engages a finger 29 so as to be raised thereby when 35 the lever is swung. Each latch is forced downward by a coiled spring 32 attached thereto and coiled about the shaft 31 to which they are also secured, as shown in detail in Fig. 5.

40 Each latch depends normally into the path of a keeper 34 projecting up from the rear end of the correlated rack bar 12 and acts to prevent the forward movement of said rack bar when the yoke is swung, unless 45 said latch is raised. I have shown five number wheels and their component parts and the wheel nearest the adding machine would be termed the right hand wheel and the other wheels therefore would be spoken 50 of as the wheels to the left. The gaps of the wheels being in printing position it is obvious that where a number other than zero is to be printed to the left of one or more wheels to the right thereof, said wheels 55 to the right must be revolved so as to print zero unless individually adjusted to print a number. For instance if it is desired to print 400 it is merely necessary to bring the 4 on the third wheel to left into printing position if the wheels to the right are 60 adjusted to each print zero. To carry out this feature each latch 30 has a laterally projecting finger 33, except the latch at the extreme right. Each finger projects to the 65 right and engages under the next adjacent

latch to the right which it lifts when it is lifted by the latch to which it is attached. It will be seen that if the latch 30 to the extreme left was lifted all the latches to the right would be lifted. The detents 17 70 are spaced ahead of the lugs 15 sufficiently to permit the bars 12 to move forward far enough to revolve the wheels to print zero when the latches are lifted.

It is obvious that various devices for inking the wheels could be provided and I have shown as an illustration an inking ribbon 36 mounted on spools 37 and passing down each side of the carrier and under the same transversely of the number wheels. Ribbon 80 bars 38 extend longitudinally of the carrier on each side thereof and have their rear ends pivoted on ears 39 depending from the side of the carrier. These bars support the ribbon as shown and are supported by 85 spring pressed uprights 41 surrounded by coiled springs 40 yieldably holding the bars as shown. When the carrier is swung down the bars yield upward. One of the uprights 40 is extended and attached to a yoke 42 90 loosely hinged on the shaft of one of the spools. A ratchet 43 is secured to the shaft of the spool and engaged by a spring pawl 44 mounted on the yoke as is shown in detail in Fig. 3. The ratchet is held against 95 backward movement by a pawl 45. The operation of the yoke and pawl and ratchet is obvious.

In the drawings I have shown a type of adding machine which has vertically movable type-bar carriers 50. These bars are displaced upwardly a sufficient distance to bring the proper type bar or printing plunger into position to be operated to print the desired number. It is obvious that in all 100 adding machines there are parts which are moved either to print certain numbers or to add the same by operating accumulating wheels. In operating my attachment it is only required that connection be had with 105 some of these parts and it is not essential that the connection be made to the carrier 50.

In attaching to the style of adding machine shown I mount an arch member 51 over the type-bar carriers and pass wires 52 115 through the member. To each carrier a wire is secured. These wires pass through flexible tubes 53 which bear on the arch member and have their opposite ends bearing on a transverse supporting bar 54 mounted in the 120 upper rear end of carrier 4. The tubes or sleeves cannot be displaced longitudinally and merely act as casings or housings for the wires. The opposite end of each wire is attached to the rear end of one of the levers 125 25, the springs 27 holding the wires taut. Proportionately as a carrier 50 is raised or elevated, the spring 27 of the correlated lever 25 swings the lever so that its detent 130 17 is elevated.

It will be seen that if a carrier 50 is raised to the type bar for printing 9 into position, its correlated wire 52 will be given sufficient slack to permit the spring 27 of the correlated lever 25 to swing said lever so that its detent 17 will be elevated as shown in dotted lines in Fig. 4. With the detent in this position its lower end will be in the path of the highest step 16 which would permit the correlated rack bar 12 to move forward until said step engaged the detent.

For swinging the yoke 21 a wire 55 is attached to the one side of the yoke and passed through a bar 56 as shown in Fig. 4. The wire passes through a tube 57 which has its opposite end bearing against a housing 58 which I mount on the rear of the adding machine about the platen spacing arm 60. This wire is pulled so as to swing the upper end of the yoke 21 rearward and is moved in a direction opposite to that of the wires 52. It may be attached to any part of the adding machine having the necessary movement. As shown in Fig. 1 one end of the wire 55 passes through the housing and the plunger 59 which operates the platen arm 60. The end of the wire is headed and normally spaced from the part 59 to permit an initial movement of the latter without operating the wire. This is done to permit the carriers 50 to reach the limits of their movements before the yoke 21 is swung. By this arrangement the lever 25 may be adjusted and the latches lifted before the bars 12 are released.

The adjustment of the wheels whereby numbers printed or listed by the adding machine are duplicated and would be printed when the carrier 4 was swung downward or depressed, but no means for depressing the carrier has been described. It is pointed out that the means for depressing the carrier would naturally depend upon the manner of operation of the adding machine. If the machine was manually operated, the attachment could be likewise operated or if the machine was electrically operated, the attachment could be electrically operated. I have not illustrated the former, but have shown the latter as an example.

On the frame 1 and near its forward end I mount an arched frame 61 on which a solenoid 62 is secured. The solenoid is provided with a depending armature 63 which is expelled when the solenoid is energized. The armature has its lower end attached to a cross bar 64 mounted on the carrier 4. When the solenoid is energized it will swing the carrier downward with a sharp movement whereby the characters on the wheels 10 will print through the ribbon 36 on whatever medium is placed on the shelf 5 thereunder. As a cushion a strike strip 65 is laid on the shelf. For returning the carrier 65 I provide an arm 66 extending from the rear

end thereof and attached to the upper end of a coiled spring 67 which has its lower end secured to a bracket 68 secured to and projecting from the rear edge of the shelf. This spring is under tension. For limiting the upward swing of the carrier 4 a stop screw 69 is mounted in the frame 1 in the path of the carrier.

Circuit wires A and B lead from the switch of the adding machine (not shown). The wire A is connected with the solenoid 62 and the wire B leads to a binding post 70 of a spring contact 72 which lies over the latch 30 at the extreme right of the attachment, while a wire C leads from a post 71 on said latch. By this arrangement the circuit cannot be closed until said latch is elevated so that one or more keys of the adding machine must be depressed before the attachment can be operated. Thus idle operations of the machine for spacing and other purposes will have no effect on the attachment.

The wire C leads to a contact 73 mounted on an angular support 74 depending from the bracket 68. A spring held rock shaft 75 is mounted in the bracket and has a contact arm 76 fastened thereon and normally held away from the contact 73. When the shaft is rocked it is placed under the tension of its spring which returns it to normal position when the shaft is released. A stop arm 77 is fixed on end of the shaft and engages a stop screw 78. A wire D leads from the arm 76 to the solenoid. The shaft 75 is rocked to bring the arm 76 into engagement with the contact 73 by means of a dog 79 which engages in the notch of a disk 80 fixed on the shaft. This dog is pivoted on a lever 81 loosely mounted on the shaft. At the dog end of the lever a coiled spring 82 is attached thereto and has its opposite end secured to the support 74; while to the opposite end of the lever a wire 84 is secured which passes through the part 74. A flexible tube 85 leads from the support and houses the wire. The tube terminates at the part 58 but the wire passes through the same and is attached to the part 59. When the part 59 moves inward it pulls the wire 84 which swings the lever 81 which through its dog 79 rotates the disk, whereby the disk rocks the shaft 75 and closes the circuit. When the carrier 4 is depressed a chain 83 depending from the arm 66 pulls the dog from the notch of the disk and permits the spring actuated shaft 75 to return to normal and to swing the arm 76 from the contact 73 thus breaking the circuit. It will be apparent that during the swinging of the arm 76 and prior to its engagement with the contact 73 the circuit through the latch 30 will have been closed and the wheels adjusted to their printing position. By adjusting the screw 78 the swing of the arm 130

76 may be varied and the operation controlled.

It will be readily comprehended that various well known mechanical devices could be substituted for the solenoid and switch and the manner of depressing the carrier 4 varied according to the conditions and desires of the manufacturer.

As an illustration of the operation of the 10 attachment we will suppose that the operator has inserted a sheet of paper under the carrier 4 and has depressed the keys of the adding machine to add 20960. When the switch (not shown) of the adding machine 15 is closed to set the parts of the latter in operation the carriers 50 will be elevated. The extreme left-hand carrier 50 will be elevated to bring the numeral 2 into printing position whereby the wire 52 attached to the 20 extreme left-hand lever 25 will be moved sufficiently to allow the spring 27 to pull the lever downward so that the detent 17 at its opposite end will be elevated. The lower end of said detent will be positioned in the 25 path of the third step 16 of its correlated lug 15.

When the lever 25 is swung its finger 29 will lift the correlated latch 30 whereby the 30 circuit will be closed through the contact 72 and at the same time all the other latches to the right will be lifted through the agency 35 of the fingers 33. The rack bars 12 however will not be released as the yoke 21 is still in engagement with the arms 18. The second carrier 50 to the right and the extreme right-hand carrier 50 will not be elevated as zero is the character to be printed, but the correlated rack bars 12, as before explained may move far enough to bring the 40 zeros of their wheels 10 into printing position. The third carrier 50 to the right will be elevated to its limit to bring the 9 into printing position; while the correlated lever 25 through its wire 52 will be swung to 45 bring its detent 17 into the path of the tenth step of the lug 15 associated therewith. The fourth carrier to the right will be adjusted to bring the 6 into printing position and the correlated lever 25 will be adjusted in harmony therewith.

The carriers 50 having been elevated and the levers 25 positioned the adding machine is ready to print. When the carriers 50 began their upward movement the part 59 55 of the adding machine started its inward movement whereby the wire 84 was pulled through the housing 58 and tube 85 and began swinging the contact arm 76 through the agency of the lever 81, dog 79, disk 80, 60 and shaft 75. During the operation to the point described there has been no movement of the wire 55, but after the levers 25 are positioned the part 59 engages the headed end of the wire 55 and pulls the 65 same, whereby the yoke 21 is swung and the

springs 19 permitted to draw the rack bars 12 forward until the various steps 16 of the lugs 15 impinge the detents 17. It is obvious that the wheels 10 will be revolved to bring the desired numerals and characters 70 into printing position.

Just prior to the printing operation of the adding machine the contact arm 76 engages the contact 73 and closes the circuit through the solenoid 62, whereby the carrier 4 is 75 swung downward and 20960 printed on the sheet thereunder. As the carrier reaches the limit of its downward swing the chain 83 pulls the dog 79 from the notch of the disk and permits the spring actuated shaft 80 75 to swing the arm 76 back and break the contact so that the spring 67 may return the carrier upward until it strikes the stop 69. As soon as the printing operation of the adding machine is complete the carriers 85 50 are lowered and the part 59 withdrawn. The wires 52 will pull the levers 25 up to their normal positions and at the same time the wire 55 having been liberated, the springs 23 will return the yoke 21 whereby 90 the rack bars will be returned and the wheels reversed to their normal position. When the levers 25 are restored the springs 32 swing the latches down into the path of the keepers 34 and the circuit will be broken at 95 the contact 72.

What I claim, is:

1. In an exterior printing attachment for adding machines, the combination with movable elements of an adding machine which are operated to perform additions, of a movable support, a plurality of adjustable printing units mounted on the support, means for adjusting the units to printing positions having provision for operative connection 100 with said movable elements of the adding machine, and means for bodily moving the support to perform the printing operation.

2. In an auxiliary printing attachment for adding machines, the combination with movable elements of an adding machine which are operated to perform additions, of a plurality of printing elements, means for setting said elements to print numerals duplicating the additions accumulated in the 105 adding machine, means operated by elements of the adding machine for limiting the operation of the setting means, means operated by the elements of the adding machine for releasing the setting means and acting to 110 return the same to their normal position after they have performed their functions, and means operated through the agency of the adding machine whereby the printing elements print the sum added by the adding 115 machine.

3. In an auxiliary printing attachment for adding machines, the combination with movable elements of an adding machine which are operated to perform additions and in- 120 125 130

cluding the printing plungers and their carriers, of a plurality of printing elements, means for setting said elements to print numerals duplicating the additions accumulated in the adding machine, means for limiting the setting means having positive connection with the carriers of the printing plungers, whereby the printing elements are adjusted in harmony with the said carriers, 5 means operated by the elements of the adding machine for releasing the setting means and acting to return the same to their normal position after they have performed their functions, and means operated through the 10 agency of the adding machine whereby the printing elements print the sum added by the adding machine.

4. In an auxiliary printing attachment for adding machines, the combination with the 20 printing plunger carriers and other elements of an adding machine which are operated to perform additions, of a plurality of printing wheels each having a gap and normally in printing position, means for individually revolving the wheels to bring numerals on their peripheries into printing position, said revolving means being under tension, stops for limiting the movement of the revolving means and having operative connection with the carriers of the adding machine, a release device operated by the adding machine to move out of the path of the revolving means, and means for returning the releasing means to restore the revolving 25 means to normal position.

5. In an auxiliary printing attachment for adding machines, the combination with mov-

able elements of an adding machine which are operated to perform additions, of a plurality of printing wheels, means for revolving the wheels to bring the proper numerals into printing position, displaceable members operated by the elements of the adding machine for limiting the operation of the wheel revolving means, a swinging member normally holding the wheel revolving means in restraint and operated by the elements of the adding machine and also acting to return the wheel revolving means to its normal position after it has performed its function, 40 and means operated through the agency of the adding machine whereby the printing wheels print the sum added by the adding machine.

6. In an auxiliary printing attachment for adding machines, the combination with the movable elements of an adding machine which are operated to perform additions, of a plurality of printing wheels, means operated by the elements of adding machine for 55 setting the wheels to printing positions, a support carrying the wheels and mounted to be displaced whereby the printing wheels perform their function, and mechanism for displacing the support including an electro-magnet, a switch for closing the circuit through the magnet, means operated by the elements of the adding machine for closing the switch, means operated by the support for releasing the switch to break the circuit, 60 and means for returning the support to its 65 normal position.

In testimony whereof I affix my signature.
JACK L. WALKER.
